UNITED STATES PATENT OFFICE.

ALMET REED AND BARTLEY T. MULLIGAN, OF NEW YORK, N. Y.

IMPROVEMENT IN KNITTING-MACHINES.

Specification forming part of Letters Patent No. **158,313**, dated December 29, 1874; application filed December 22, 1874.

To all whom it may concern:

Be it known that we, ALMET REED and BARTLEY T. MULLIGAN, both of the city, county, and State of New York, have invented a new and useful Improvement in Knitting-Machines; and we do hereby declare the following to be a full, clear, and exact description thereof, which will enable those skilled in the art to make and use the same, reference being had to the accompanying drawing forming part of this specification, in which drawing—

Figure 1 is a plan view of a knitting-machine provided with our improvements. Fig. 2 is a side elevation. Fig. 3 is a central vertical section of the machine. Fig. 4 is an end elevation, showing more in detail than in the previous figures the shifting apparatus, by which the direction of motion of the pattern-cylinder is governed automatically. Fig. 5 shows an improved device for operating the "wiper," the old method being shown in Figs. 1, 2, and 3.

Similar letters indicate corresponding parts.

This invention relates to that class of knitting-machines in which a pattern-cylinder is employed for changing the direction of the motion of the needle-cylinder; and consists, among other things, in an eccentric on the driving or cam shaft, combined with a jointed lever of the first order, for imparting motion to the shaft or gear which drives the pattern-cylinder, the end of the lever being made to work on the principle of an "escapement," whereby the gear or shaft, and consequently the pattern-cylinder, has imparted to it a regulated step-by-step motion, and its momentum is always controlled. It also consists of a peculiar device for communicating motion to the pattern-cylinder from the said gear or shaft by means of a system of bevel-gears and double sliding clutch, whereby the pattern-cylinder is rotated in one direction, or the opposite direction, according to the connections that are made by the clutch. The clutch is actuated from the pattern-cylinder itself by means of bevel-faced shifting-pins arranged at suitable points on its periphery, according to the work to be knitted, the said pins acting against a rack-rod, which is raised by the pins, and

whose teeth engage a spur-gear sliding on a feather on a rock-shaft provided with a cam, which lifts a spring-latch, whose office it is to lock the double sliding clutch whenever either of its ends is engaged with the clutch-gear. The double sliding clutch has an arm, which extends from it to a rod, to which it is attached. Around this rod are placed two independent spiral springs, which are separated by an arm extending from a traveling nut, hereinafter mentioned. The outer end of one of the springs abuts against the clutch-arm, and the inner end against the arm of the nut, which arm is arranged to slide on the rod between the springs, and extends from a traveling nut, that runs upon a screw that is turned either toward the right or the left, according to which end of the clutch is engaged. The other spring is arranged on the rod on the other side of the arm, and abuts, by its outer end, against an adjustable collar on the rod. The said rod is arranged in its bearings in such a manner that it can be moved endwise the same distance as the double clutch, to which it is rigidly secured by the clutch-arm, before mentioned.

When the spring-latch is raised, the clutch-arm, and the rod to which said arm is connected, is pushed one way or the other by the springs, according as one or the other has been compressed by the nut-arm, and the clutch is moved from one clutch-gear to the other. The clutch-gears revolve continuously in opposite directions, one of them being formed on a hollow shaft, which turns loosely on an inner shaft, to which the other clutch-gear is secured.

When the clutch is shifted, the direction of rotation of the pattern-cylinder is reversed, and, since the screw is rotated directly from the same gear-teeth on the pattern-cylinder, with which the pinion on the sliding clutch is engaged, it follows that the direction of rotation of the screw is also reversed at the same time. The nut on the screw carries the rack-arm, which is actuated by the shifting-pins, and also another rack-arm, which is actuated by those patterns on the cylinder which reverse the needle-cylinder. The last-mentioned

rack-arm engages a sliding spur-gear on a rock-shaft, which is also, like the rock-shaft heretofore referred to, provided with a cam that lifts a lever connected with the yarn-guide, and the yarn-guide has lateral extensions at each end, which carry pins that work in inclined slots in sliding aprons, whose office it is to intervene between the geared ring on the needle-cylinder and the driving-pawls that engage said geared ring on either side, and rotate the needle-cylinder, or the inclined slots can be made in the extensions, and the pins placed on the aprons. The said driving-pawls are moved by cams or eccentrics on the cam-shaft. Our invention also consists in an improved means for operating the wiper, which wipes or pushes the work down to the bases of the needles as the goods are knitted.

The letter A designates the frame of the machine, and B a needle-cylinder, provided with vertical grooves, in which the needles *a* move up and down as they are successively brought into action. The needle-ring is inclosed within a frame, D, in such a manner that it can be rotated or turned in either direction as the direction of the knitting is changed. The up-and-down movements of the needles are effected by a bar, E, whose front face is grooved to receive the projections of the needles, which come opposite to it as the needle-ring is turned in one direction or the other, said bar E being moved up and down by a vertical slide, F, working in guides *b b*, the slide F being operated from the driving-shaft G by means of an eccentric, *d*, connecting-rod *e*, and rocking arms *f f'*, fixed on a shaft, *g*, the end of the arm *f'* being connected to the slide F by a connecting-rod, *f''*, made in two parts, and connected by a nut, *f''*, having a thread on its exterior and interior, one right, the other left, the inner thread working on a stem on the end of one part, and the outer thread working within the other part, in such a manner that by the rotation of the nut the connecting-rod is either lengthened or shortened, and thereby the extent of motion imparted to the needles is controlled and regulated.

The needle-pressers Y, the detent T for engaging the toothed ring N of the needle-cylinder, the spring-pawls *q q*, and their levers P P for driving the needle-cylinder, with their actuating cams or eccentrics on the driving-shaft G, remain as heretofore constructed.

The shaft H, (on which the pattern-cylinder H' is supported,) has on one end a gear-wheel, *i*, which is driven from an eccentric, 2, on the shaft G by means of a jointed lever, *g¹*, of the first order, having its fulcrum at *g²*. The lever *g¹* is constructed and operates on the principle of an escapement, causing the gear *i* to move one tooth at a time, and locking it after each movement, so that it can neither move onward from the effect of the momentum, nor react from the effect of resistance. The shorter

end of the lever is made with a beveled spring, propelling tooth *g³*, working in a socket, *g⁴*, in the said lever, and is provided with a spring-detent, *g⁵*, working through ears *g⁶* formed on the same part of the frame of the machine which supports the fulcrum of said lever. The shorter end of said lever is provided with an extension, *g⁷*, which extends between the ears *g⁶*, and is slotted to allow the detent to go through it; and, between the said extension *g⁷* and the forward ear *g⁶*, said detent is surrounded by a spiral spring, one end of which is fastened to the detent, while said detent on the part between said extension and the back ear *g⁶* is provided with a pin, *g⁸*, against which the extension strikes, when the lever is vibrated in the direction of the arrow marked thereon, and the detent is thereby withdrawn from engagement with the gear, and allows the gear to be moved by the spring-tooth. But the spring-tooth and detent are so arranged that before the detent is withdrawn the bevel of the spring-tooth is carried, by the vibration of the lever, against and past the adjacent tooth of the gear-wheel, so as to engage that tooth by its straight edge, the detent meanwhile holding the wheel stationary; and so soon as the beveled tooth has passed to that position the continued vibration of the lever operates to withdraw the detent, and allow the reverse movement of the lever to advance the gear-wheel the distance of one tooth, when the detent is released, and is again pushed by its spring between adjacent teeth of the gear.

The gear-wheel *i* is supposed, in the drawing, to be moving in the direction of the arrow, Figs. 2 and 4, and it follows that the pinion *j*, engaged by it, will be turned in the opposite direction.

The pinion *j* is fast on the sleeve or hollow shaft *j¹*, on whose inner end is formed the clutch-gear *j²*, while its outer end has fixed thereon the bevel-gear *j³*, which engages the intermediate horizontal bevel-gear *j⁴*, and through the latter communicates motion, by the bevel-gear *j⁵*, to the shaft *j⁶*, which extends through said hollow shaft *j¹* and through the sliding clutch *j⁷*, and has fixed on its inner end a clutch-gear, *j⁸*. The clutch *j⁷* has a wide pinion, *j⁹*, formed upon it, in such a position that it will always engage the gear-teeth *H²* placed around the pattern-cylinder *H¹*. The clutch carries also an arm, *j¹⁰*, which extends upward over the pattern-cylinder to the rod or bar *s*, to which it is fastened; and the clutch-arm and rod are held stationary after every reversal of the clutch by means of a spring-latch, *s¹*, which has at its end a pin, which enters holes in the arm, so that the rod *s* and the clutch are locked and prevented from moving endwise. The rod or bar *s* is arranged so that it can slide endwise a distance equal to the motion given to the clutch, and is provided with two independent spiral

springs, s^2 s^3 , which are separated from each other by an arm, u , made with an eye, so as to embrace and slide on the rod. The inner ends of the springs bear against the sides of the arm u , and the outer end of the spring s^3 bears against the clutch-arm j^{10} , while the outer end of the spring s^2 bears against an adjustable collar on the left-hand end of the rod. The arm u extends from a nut, u^2 , (of which it is a part,) that travels on the screw u^3 , which is revolved from the gear H^2 of the pattern-cylinder through the pinion u^4 , fixed on the screw. The arm u , that extends from the nut, carries on its side (see Fig. 1) a spur-gear, u^5 , which is connected by a feather to the rock-shaft u^6 , (over which the said arm extends,) so that it can slide thereon; and the body of the spur-gear is made large enough to allow a rack-arm, u^7 , provided at its lower end with an anti-friction roller, to work up and down through it, the teeth of the rack-arm engaging the spur-gear, so as to rock the said shaft u^6 whenever the traverse of the nut on its screw brings the rack-arm in contact with one or the other of two shifting-pins, u^8 , which are set in holes in the periphery of the pattern-cylinder, in such positions and in such relation to each other as will cause the direction of rotation of the pattern-cylinder to be changed automatically at any desired point of the traverse of the nut on the screw, so that the machine can continue its work automatically, without requiring the attendant to effect such change of direction.

The reversal of the direction of rotation of the screw is effected, by means of the parts already mentioned, through a lifter or cam, u^9 , on the rock-shaft u^6 , which lifts the spring-latch s^1 and unlocks the clutch-arm j^{10} and rod s , which are immediately pushed along by the spring s^3 toward the right, (observing Fig. 4,) when the spring is compressed by the arm u , and are moved toward the left when the spring s^2 is compressed by said arm, the extent of movement being such as to disengage the clutch at one end, and engage it at the other.

The pattern-cylinder is provided on its periphery with pattern-bars H^3 , one or more arranged spirally, with a pitch equal to the pitch of thread of the screw, and of whatever length is desired, according to the variations required in the knitting. The pattern-bars can be changed on the cylinder, if desired, for changes in the work; or different cylinders or skeletons, each having a different length or different position of pattern-bars, can be provided and placed on the cylinder-shaft. The pattern-bars H^3 furnish the means for shifting the yarn-guide K and for oscillating or changing the direction of the needle-cylinder. These actions are accomplished by a rack-arm, x , whose end, provided with an anti-friction roller, rests on the periphery of the pattern-cylinder, and, when a pattern-bar, H^3 , lies in its path, the rack-arm is lifted by it and turns a spur-gear, x^1 , which is connected,

by means of a feather, with a rock-shaft, x^2 , on which is a lifting-cam, x^3 , that operates the jointed lever, x^4 , and thereby changes the position of the yarn-guide K . The spur-gear x^1 , like the spur-gear u^5 , is connected to the nut u^2 , and is carried with it to the right or left, so as to come in line with and meet the pattern-bars. The yarn-guide K has on each side extensions K^1 K^1 , which are each provided with inclined slots K^2 near their ends, that receive studs formed on aprons r r^1 , which latter are, respectively, moved by the action of the studs in their slots so as to intervene between one or the other of the driving-pawls q q and the teeth on the needle-ring when one or the other of said pawls is to be brought into or out of action. After the pattern-bar that caused this movement has passed from under the rack-arm, the lever x^4 is pressed down by a weight or spring as the cam on the rock-shaft x^2 falls, and the driving-pawl, which was in operation before such movement is restored to action, and the rotation of the needle-cylinder proceeds in the direction in which it had been running before the change occurred.

The wiper 1 is made of rigid material, such as metal, wood, or hard rubber, in contradistinction from yielding material, and we operate it from the cam-shaft by means of the strap of the eccentric d , which works the needle-slide F , and by an independent cam, in the following manner:

On the top of the strap d' we arrange a rising arm, y , carrying an anti-friction roller, and the arm y is surmounted by a yoke, y^1 , within which it oscillates with the movements of the eccentrics. From the yoke y^1 extends a lever, y^2 , working on a sliding fulcrum, y^3 , and the other end of the lever is adjustably connected to a vertical arm, y^4 , that extends upward from the wiper 1. The revolution of the eccentric d causes the yoke y^1 and lever y^2 , and with them the wiper 1, to be oscillated back and forth, and, in addition to this motion, we give the lever and wiper simultaneously a rising and falling motion by means of a lever, y^5 , whose free end, y^6 , comes up against the under side of the lever y^2 in front of its fulcrum, its other end being in contact with a cam, y^8 , formed on the cam-shaft G , as shown in Fig. 5. The wiper is pressed downward by means of the spring y^7 , which is arranged under the back end of lever y^2 , so as to keep the front end constantly bearing downward with a gentle pressure.

In this manner a compound motion is imparted to the wiper, the action of the under lever y^5 upon the lever y^2 being so timed that the wiper is lifted at the time the wiper has reached its lowest position and is being moved away from the needles.

What we claim as new, and desire to secure by Letters Patent, is—

1. The escapement lever g^1 , provided with

the spring-tooth g^3 and spring-detent g^5 , in combination with the cam-shaft G and driving-shaft H, substantially as described.

2. The sliding clutch j^7 and the clutch-gear j^2 and j^3 and their shafts, in combination with the nut u^2 , screw u^3 , pattern-cylinder H¹, and springs s^2 s^3 , substantially as described.

3. The combination of the screw u^3 , nut u^2 , spur-gear x^1 , and rock-arm x with the yarn-guide K, substantially as described.

4. The combination of the sliding clutch and clutch-gears, the pinion j , bevel-gears j^3 j^4 j^5 ,

and shafts j^6 j^1 with the pattern-cylinder, substantially as set forth.

5. The levers y^2 y^3 , arranged and operated as described, in combination with the wiper 1, as set forth.

This specification signed by us this 12th day of March, 1873.

ALMET REED.
BARTLEY T. MULLIGAN.
